Primary Examiner — Eric Goodman*Assistant Examiner* — Amy Wierenga(57) **CLAIM**

The ornamental design for a toner cartridge seal, as shown and described.

DESCRIPTION

FIG. 1 is a perspective view of a toner cartridge seal showing my new design;

FIG. 2 is a left-side elevational view thereof;

FIG. 3 is a right-side elevational view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a front elevational enlarged view for ease of disclosure thereof;

FIG. 9 is a rear elevational enlarged view for ease of disclosure thereof;

FIG. 10 is a left-side elevational view thereof; and,

FIG. 11 is an enlarged left-side elevational view so indicated in FIG. 10 thereof.

The dot dash broken line indicates cutoff boundaries for enlarged detailed portion views and form no part of the claimed design.
